SLASHER WINDING MECHANISM AND ROTATING BEAM POSITIONER

Evan V. Quinn and Evan V. Quinn, Jr., Rye, N. Y., assignors to Unistel Textile Machine Corporation, Pert Chester, N. Y.

Application March 25, 1955, Serial No. 496,848

11 Claims. (Cl. 28—28)

This invention relates to a textile winding machine and more particularly to a rotating mechanism for winding a multiplicity of parallel warp yarn ends on a succession of loom beams.

This invention is a continuation-in-part of our parent application, Serial No. 411,746 filed February 23, 1954.

It is a primary object of the present invention to provide a mechanism for rotating loom beams without stopping or slowing down the operation of a warp yarn sizing machine known as a textile slasher.

As is known the textile slasher is a machine that consists of a creel, a size box, a dryer, a delivery roll and a winding mechanism. The yarn ends which usually number from one thousand to eight thousand are held in parallel relationship and delivered from the creel to the size box and dryer and then to the delivery roll for winding on a succession of loom beams.

Heretofore, the slasher was stopped when each loom beam was full of yarn ends. The operator then cut the warp yarn ends, removed the full loom beam, replaced the full loom beam with an empty loom beam, fastened the yarn ends to the core of the empty loom beam, and finally started the slasher again. This operation was repeated until the set of yarn ends ran out. Thus, depending upon the diameter of the loom beams, from 15 to 30 loom beams had to be changed in order to complete a set. The difficulty and disadvantage of the aforesaid procedure was that while the slasher was stopped in order to carry on the operation of replacing a full loom beam with an empty loom beam the warp yarns remaining in the slasher picked up excess size and also became over dried. Thus, these warp yarns when woven into cloth have more of a tendency to break in the loom and the cloth so woven may be of inferior quality.

The present mechanism has been devised in order to overcome the disadvantages of known structures. Although industries manufacturing paper, cloth and other sheet and metal products have used continuous winding machines none of these machines are applicable to the winding of warp yarns on loom beams because of the special problems arising therewith which are hereinafter enumerated. In this connection, the warp yarns, which number in the thousands, must each lay parallel and have the same tension thereon as the other warp yarns. This presents a problem of winding, cutting from a full loom beam, and fastening to a succeeding loom beam which does not exist for materials in sheet or web form. Moreover, the yarn ends have a certain amount of elasticity so that when the yarn ends are cut under tension they must be held and they must also be held while fastening to a succeeding loom beam or otherwise the yarn ends will rebound and tangle. It is furthermore essential in winding yarn ends that the loom beam does not stop winding under tension during the positioning of the empty beam in the former position of the full beam otherwise the yarn ends will lose their tension and tangle. The mechanism according to the present invention recognizes

the above problem and has succeeded in providing an effective solution therefor.

Another object of the present invention is to provide a winding and beam-changing mechanism which will considerably lower the amount of warp yarn wastage per set of warps.

It is still another object of the present invention to provide a textile slasher with a beam-positioner and winding mechanism which incorporates a draw bar tensioning device, a yarn cutter, and a fastening device for securing yarn ends to a loom beam.

It is another object of the present invention to provide a combination tension positioner and accumulator roll which acts to maintain sufficient tension on the warp yarn ends to keep them from tangling, to pull the yarn ends taut on the barrel of the empty beam in fastening position thereof and to accumulate warp yarn ends delivered by the slasher delivery roll while both beams have temporarily stopped at the time of cutting and fastening of the warp yarn ends to the empty loom beam.

Another object of the present invention is the provision of a winding and loom beam changing mechanism for cutting, fastening and winding yarn ends on a beam which is simple, rapid and effective for the purposes intended.

The above and other features, objects and advantages of the present invention will be fully understood from the following description considered in connection with the accompanying drawings.

Fig. 1 is an end elevation view of the textile winding machine embodying the present invention;

Fig. 2 is a front elevation view of an electrical resistance type cutter according to the invention;

Fig. 3 is a front elevation view of an alternate type of knife cutter in accordance with the present invention;

Fig. 3a is an end elevation view thereof;

Fig. 4 is a perspective view of the combination tension positioner and accumulator roll thereof, and

Fig. 5 is a front elevation view, partly in section, of the present textile winding machine and associate elements,

Fig. 6 is a front elevation view of the loom beam and the fastener shoe;

Fig. 7 is a detailed view of a portion of Fig. 2, and Fig. 8 is a side elevation of Fig. 7.

Referring specifically to the drawings and more particularly to Figs. 1 and 5, the textile winding machine embodying the present invention comprises a pair of main support pedestals 10 having a pair of bearings 12 mounted thereon. A spindle 14 is mounted with both ends supported in bearings 12. Spindle 14 is also provided with a pair of lateral arms 16 and 18 on opposite ends thereof but spaced from bearings 12. On the right hand side of Fig. 5 is shown a sprocket 20 and a positioning motor 22 which serves to drive sprocket 20 through a well-known sprocket chain which in turn rotates spindle 14 with the lateral arms 16 and 18 thereon. Lateral arm 18 mounts a pair of tail stocks 24 which are slidably removable in lateral arm 18. Similarly, on lateral arm 16 is mounted a pair of corresponding head stocks 26. Thus, each pair of head stocks and tail stocks are so placed that a pair of loom beams 28 and 30 having heads 28a and 30a may be placed thereon and maintained on the lateral support arms in spaced relationship (see Fig. 1). Each of the head stocks 26 may be driven separately and individually by means of winding power motor 32, a sprocket 34 mounted on a countershaft 36, a sprocket 38 also mounted on the countershaft 36 and a sprocket 40 mounted on the shaft 42 of each head stock 26 through a clutch 44. Shaft 42 is supported in bearings 43 depending from lateral arm 16. Hence, the motor 32 drives each head stock through sprocket 34, sprocket 38,

and finally sprocket 40 through clutch 44. It should be noted that the sprocket 34 drives both head stocks 26 separately and individually through clutch 44. The actual driving force applied to both loom beams is effected by means of a loom beam driving dog 46 which in Fig. 5 is shown removably engaged with loom beam head 28a. Figs. 1 and 4 illustrate binder roll 48 and delivery roll 50 for the delivery of a multiplicity of parallel and individual warp yarn ends 52 to the textile winding machine embodying the present invention.

As clearly seen in Fig. 1 the warp yarn ends are wound on the right hand side of the figure while the empty loom beam 30 is positioned on the left hand side of the figure. Thus, loom beam 28 is rotated by means of winding power motor 32 since its associated clutch 44 is engaged, while loom beam 30 is stationary since its associated clutch 44 is disengaged. After a given length of warp yarns have been wound on loom beam 28 its clutch is disengaged and the warp yarns 52 are clamped and cut in a manner to be described in detail hereinafter, and the yarn ends being furnished from the delivery roll of the textile slasher which is still in uninterrupted operation are fastened to empty loom beam 30 by means which will be described more fully hereinafter. Thereafter, the lateral arms 16 and 18 are rotated by positioning motor 22 so that loom beam 30 takes the position formerly occupied by loom beam 28, the full loom beam 28 having been replaced by an empty loom beam which then has the position formerly occupied by loom beam 30. Thus, there is a rotation of the lateral arms preferably of 180° but not necessarily limited thereto in order to change positions of the loom beams. Further details concerning the operation of our winding mechanism are clearly set forth in our parent application, Serial No. 411,746.

Referring more particularly to Fig. 4 and the left hand side of Fig. 1, the structure shown therein includes a tension positioner and accumulator roll 54 which is supported in a pair of guide members 56 having elongated vertical slots 58. The roll 54 rests on the warp yarns 52 coming off the delivery rolls, the roll 54 being free running in the slots 58 of guide 56. When the warp yarn 52 is being wound on a rotating loom beam the warp yarns are in the position shown in dotted lines in Fig. 4 in a more or less straight line to the rotating loom beam with the roll 54 in the top portion of the slots 58 and resting on the warp yarns 52. However, when both loom beams stop winding and the yarn ends are being cut and fastened to the empty loom beam, the yarn ends being delivered from the delivery roll 50 of the textile slasher form a loop and the roll 54 freely movable in slot 58 drops downward under the influence of gravity to continue to rest on warp yarns 52 as shown in full lines in Fig. 4 thereby maintaining sufficient tension on the warp yarns 52 to prevent tangling of the individual yarns. Tension positioner and accumulator roll 54 also function to pull the yarn ends taut over the spindle of the empty loom beams in an even lay for fastening thereto. In addition, roll 54 acts to accumulate the excess yarn ends until the empty beam is ready to wind. When the clutch associated with the empty loom beam is engaged, the standard textile slasher drive will be operated at high speed to build up preset yarn tension. Therefore, the accumulated yarn ends are wound rapidly on the loom beam and the roll 54 travels in slots 58 to its dotted line position and the loop of yarn ends disappear. It should be noted that the tension positioner and accumulator roll 54 acts to always maintain sufficient tension on the warp yarn ends in order to keep them from tangling; functions to pull the yarn ends taut over the empty loom beam for fastening thereto; accumulates the warp yarn ends delivered by the delivery rolls 48 and 50 while both loom beams have temporarily stopped winding at the time of cutting and fastening the warp yarn ends to the empty loom beam.

Referring now to the cutting mechanisms of the pres-

ent invention, the type of cutter illustrated in Fig. 2 is the electric resistance type which includes a metal tube 60 having an electrical resistance wire 62 therein but not in contact with the inner wall of tube 60. The electrical resistance wire 62 is supplied with electrical current through a transformer 63. Heat is conducted from the wire 62 through a material which is a conductor of heat and not of electricity (not shown) to the tube 60. Thus, the metal tube 60 when dropped into engagement with a multiplicity of warp yarns will sever the same by burning or scorching through them. The electrical resistance cutter is mounted on a frame 64 through springs 66. The mechanism for elevating and lowering the cutter frame and cutter consists preferably of a piston 68, a cutter latch 70 and a cutter knock-off 72. As seen in Fig. 1 an upper draw bar 74 and a lower draw bar 76 serve to tension the warp yarns over the lower bed 78. The upper bed 80 upon the lowering of the cutter to a position in close proximity but not touching the warp yarns 52 is further dropped into clamping engagement with the warp yarns 52 by means of an electrical actuator 82 (Fig. 2). Thus, the actuator 82 translates the upper bed 80 the remaining distance necessary for it to contact the lower bed 78 and clamp the warp yarns therebetween. The cutter is also translated by the actuator 82. Accordingly, at or just preceding contact of the upper and lower beds the cutter latch 70 is disengaged thereby permitting the cutter to drop freely through the warp yarns and thereby sever the warp yarns by burning. Thereafter the actuator 82 is de-energized and springs 66 due to their natural resilience raise upper bed 80 and through a motion multiplier 84 and the cutter itself is elevated away from engagement with the warp yarns 52.

Another type of cutter for employment with the present invention is seen in Figs. 3 and 3a. The cutter shown therein is a knife cutter having a grooved supporting element 86 provided with a fixed shear blade 88 which is permanently mounted in the groove of supporting element 86 by means of a pin 90. Also mounted in the groove of supporting element 86 and juxtaposed to fixed blade 88 is a reciprocating blade 92 which is connected to a vibrator 94. Thus, vibrator 94 causes the movable blade 92 to move rectilinearly against the fixed blade 88 and when the warp yarns are forced into the arcuate openings of the blades 88 and 92 the cutting edges thereof effectively sever these warp yarns. It should be understood that the same mechanism utilized for elevating and lowering the cutter illustrated in Fig. 4 is used for this alternate type of cutter. It is preferable to have a fairlead roller 96 on the side of the cutter remote from the slasher delivery rolls in order to guide the warp yarns on to the filling loom beam.

Referring now in particular to the fastening mechanism as seen in Figs. 1 and 5; the structure comprises an arm 98 which may be pivoted to the cutter framework structure. Mounted in the arm 98 is a solenoid for actuating the fastener 100 having a fastening shoe 102. The fastener 100 is provided with a collar 104 and a driving spring 106 contained between the collar 104 and the arm 98 and another collar 108 having a rebound spring 110 trapped between the collar 108 and the arm 98. A handle 112 is utilized in order to manually lift and lower the fastener from and to striking position. As seen in Fig. 6, the fastener shoe referred to generally by the numeral 102 includes an elongated arcuate clamping member 114 which is secured to laterally movable elements 116 on each end thereof by means of springs 118. It should be noted that movable elements 116 are bevelled at their lower outer edges 120 which co-act with the bevel on the inner edge of the loom beam heads 28a thus facilitating the driving of the fastening shoe into engagement with the warp yarn ends and thereby forcing the latter into securement on the adhesive backing fixed to the loom beam spindle while roll 54 maintains the yarn ends in an even lay thereon. Since the length of the fastening shoe 102

is variable the fastening shoe 102 is easily driven into and removed from between the loom beam heads 30a of loom beam 30. It is within the scope of our invention to provide other means on the loom beams for securing the severed warp yarn ends thereto.

Referring more particularly to Figs. 7 and 8 wherein is shown the assembly in detail employed with the electric resistance cutter illustrated in Fig. 2, it being understood that only the cutter latch 70 of the assembly is shown in broken lines on Fig. 2. In this regard, a support member 75 is secured to upper bed 80. Journalled through support member 75, cutter latch 70, and hold-back hooks 81 is a shaft 73. It should be understood that cutter latch 70 as well as holdback hooks 81 are adapted to rotate in a direction transverse to the axis of shaft 73. Thus, upon downward movement of the upper cutting bed, the assembly shown in Figs. 7 and 8 is carried along. Holdback hooks 81 engage motion multiplier arms 84 near offset rollers 83 and prevent the multiplier arms 84 from pivoting. However, when the cutter is lowered to a particular position proximate to the warp yarns 52 the cutter latch 70 is pivotally disengaged from the cutter knockoff 72 and the holdback hooks 81 are also pivotally disengaged from multiplier arms 84 thereby permitting the multiplier arms 84 to pivot about pivot points 85 while rollers 83 abut the fixed portion of the cutter. Through the action of the cutter as described the cutter undergoes a free fall movement in a downward direction and a multiplied movement in an upward direction; and the cutter itself moves a greater distance than the movement of the upper bed 80.

The sequence of operation of our invention is as follows: when one loom beam is wound full of warp yarns, the clutch associated with that beam is disengaged thereby stopping the rotation thereof. The clamping mechanism is then dropped to clamp the warp yarns between the two loom beams. The cutter is then lowered across the warp yarns thereby severing them and releasing the full loom beam. While the clamping mechanism still holds the severed ends of the warp yarns the textile slasher delivery roll continues to deliver warp yarns which slack is taken up by the tension positioner and accumulator roll so that an even lay of warp yarn ends on the empty loom beam is effected. The fastening shoe then forces the yarn ends against the adhesive backing on the empty loom beam to thereby secure the same thereto. The clutch on the empty loom beam is then engaged and the empty loom beam commences to wind. The full loom beam is then replaced with an empty loom beam and the whole unit rotated so that the loom beam positions are interchanged.

What we claim is:

1. In a textile slasher machine, a method of winding a multiplicity of parallel yieldable warp yarn ends on loom beams comprising positioning at least one pair of individually rotatable beams in spaced relationship on a movable frame, securing warp yarn ends to one of said beams, rotating said one beam, moving said frame while maintaining a constant tension on said warp yarn ends whereby said one beam takes another position, continuing the uninterrupted rotation of said one beam until a predetermined length of warp yarns is wound on said one beam, stopping the rotation of said one beam clamping said yarn ends at two spaced portions thereof, cutting said yarn ends in a region between said clamped several yarn ends, and thereafter fastening said yarn ends to the other of said loom beams without stopping the operation of said textile slasher machine, and providing means for keeping the accumulated warp yarn ends under the proper tension until a predetermined time after said other beam commences to rotate.

2. In a textile slasher machine, a method of winding a multiplicity of parallel yieldable warp yarn ends on loom beams comprising positioning at least one pair of individually rotatable beams in spaced relationship on a movable frame, securing warp yarn ends to one of said

beams, rotating said one beam, moving said frame while maintaining a constant tension on said warp yarn ends whereby said one beam takes another position, continuing the uninterrupted rotation of said one beam until a predetermined length of warp yarns is wound on said one beam, stopping the rotation of said one beam and clamping said yarn ends while said textile slasher machine delivers an uninterrupted supply of yarn ends to the other of said loom beams, clamping said yarn ends at two spaced portions thereof, cutting said yarn ends in a region between said clamped yarn ends, and thereafter fastening said several yarn ends to the other of said loom beams.

5 3. A textile slasher beam-changer and winding mechanism for delivering a multiplicity of warp yarns to a plurality of loom beams comprising a base member, a movable frame mounted on said base member and having a plurality of head stocks on one end thereof and a plurality of complementary tail stocks on the other end thereof, each complementary pair being adapted to accommodate a replaceable loom beam, a plurality of clutch mechanisms, means for driving each of said head stocks through a separate clutch mechanism, means for revolving said frame to thereby change the relative positions of said beams, at least one of said yarn beams being continuously rotated during said change of relative positions of said beams, the rotation of each of said headstocks being stopped periodically, means for clamping said warp yarns at two spaced portions thereof, means for cutting said warp yarns between said clamped

10 15 20 25 30 35 40 45 50 55 60 65 70 75

warp yarns, means for fastening said severed warp yarns to another of said loom beams, and means for continuously maintaining yarn tension of the accumulated warp yarns during the uninterrupted delivery of warp yarns from said slasher.

4. A textile slasher beam-changer and winding mechanism for delivering a multiplicity of yieldable warp yarns to a plurality of loom beams comprising a base member, a movable frame mounted on said base member and having a plurality of head stocks on one end thereof and a plurality of complementary tail stocks on the other end thereof, each complementary pair being adapted to accommodate a replaceable loom beam, a plurality of clutch mechanisms, means for driving each of said head stocks through a separate clutch mechanism, means for revolving said frame to thereby change the relative positions of said beams, at least one of said yarn beams being continuously rotated during said change of relative positions of said beams, means for continuously maintaining yarn tension during the uninterrupted delivery of warp yarns to said beam changer and winding mechanism, means for cutting said warp yarns between two of said loom beams, means for fastening said warp yarns to the other of said loom beams, and means for clamping said warp yarns at two spaced portions thereof simultaneously and immediately prior to cutting of said warp

5. A textile slasher beam-changer and winding mechanism for delivering a multiplicity of warp yarns to a plurality of flanged loom beams comprising a base member, a rotatable frame mounted on said base member having a plurality of tail stocks on one end thereof and a plurality of complementary head stocks on the opposite end thereof, each complementary pair of head stocks and tail stocks being adapted to accommodate a replaceable loom beam, a plurality of clutch mechanisms, means for driving each of said head stocks through a separate clutch mechanism, means for revolving said frame to thereby change the relative positions of said loom beams, at least one of said loom beams being continuously rotated during said change of relative positions of said beams, a movable tension positioner and accumulator roll supported by the warp yarns and for continuously maintaining yarn tension during the uninterrupted delivery of warp yarns to said beam changer and winding mechanism, means for clamping said warp yarns at spaced

7 portions thereof to maintain said warp yarns therebetween in a taut condition, and means for cutting the warp yarns between said clamped warp yarns.

6. A textile slasher beam-changer and winding mechanism for delivering a multiplicity of yieldable warp yarns to a plurality of flanged loom beams comprising a base member, a rotatable frame mounted on said base member having a plurality of tail stocks on one end thereof and a plurality of complementary head stocks on the opposite end thereof, each complementary pair of head stocks and tail stocks being adapted to accommodate a replaceable loom beam, a plurality of clutch mechanisms, means for driving each of said head stocks through a separate clutch mechanism, means for revolving said frame to thereby change the relative positions of said loom beams, at least one of said loom beams being continuously rotated during said change of relative positions of said beams, and a movable tension positioner and accumulator roll supported by the warp yarns, guide means for guiding said roll upon vertical movement thereof in said guide means to maintain continuous tension on said warp yarns during the uninterrupted delivery of said warp yarns to said beam changer and winding mechanism, means for clamping said warp yarns at spaced portions thereof to maintain said warp yarns therebetween in a taut condition, and means for cutting the warp yarns between said clamped warp yarns.

7. A textile slasher beam-changer and winding mechanism for delivering a multiplicity of warp yarns to a plurality of loom beams comprising a base member, a rotatable frame mounted on said base member having a plurality of tail stocks on one end thereof and a plurality of complementary head stocks on the opposite end thereof, each complementary pair of head stocks and tail stocks being adapted to accommodate a replaceable loom beam, a plurality of positive grip clutch mechanisms, means for driving each of said head stocks through a separate clutch mechanism, means for revolving said frame to thereby change the relative positions of said loom beams, at least one of said loom beams being continuously rotated during said change of relative positions of said beams, a movable tension positioner and accumulator roll supported by the warp yarns and for continuously maintaining yarn tension during the uninterrupted delivery of warp yarns to said beam changer and winding mechanism, and means for cutting said warp yarns between two of said loom beams, said last-mentioned means being an elongated tube heated by electrical current, a movable member being provided with resilient means for yieldably supporting said cutting means.

8. A textile slasher beam-changer and winding mechanism for delivering a multiplicity of warp yarns to a plurality of loom beams comprising a base member, a rotatable frame mounted on said base member having a plurality of tail stocks on one end thereof and a plurality of complementary head stocks on the opposite end thereof, each complementary pair of head stocks and tail stocks being adapted to accommodate a replaceable loom beam, a plurality of clutch mechanisms, means for driving each of said head stocks through a separate clutch mechanism, means for revolving said frame to thereby change the relative positions of said loom beams, at least one of said loom beams being continuously rotated during said change of relative positions of said beams, a movable tension positioner and accumulator roll supported by the warp yarns and for continuously maintaining yarn tension during the uninterrupted delivery of warp yarns to said beam changer and winding mechanism, and knife means for cutting said warp yarns between two of said loom beams, said knife means having a fixed shear blade and a cutting blade movable reciprocably in a plane parallel to the longitudinal axis of said shear blade and juxtaposed thereto, both said blades having a plurality

5 of serrations for the reception of warp yarns therein, and a pair of draw bars clamping said warp yarns to further tension the same prior to the cutting thereof.

9. A textile slasher beam-changer and winding mechanism for delivering a multiplicity of yieldable warp yarns to a plurality of loom beams comprising a base member, a rotatable frame mounted on said base member having a plurality of tail stocks on one end thereof and a plurality of complementary head stocks on the opposite end thereof, each complementary pair of head stocks and tail stocks being adapted to accommodate a replaceable loom beam, a plurality of clutch mechanisms, means for driving each of said head stocks through a separate clutch mechanism, means for revolving said frame to thereby change the relative positions of said loom beams, at least one of said loom beams being continuously rotated during said change of relative positions of said beams, a movable tension positioner and accumulator roll supported by the warp yarns and for continuously maintaining yarn tension during the uninterrupted delivery of warp yarns to said beam changer and winding mechanism, means for clamping said warp yarns at spaced portions thereof, means for cutting said warp yarns between said clamped warp yarns, a movable member being provided with resilient means for yieldably supporting said cutting means, means for fastening said warp yarns to the other of said loom beams, said last-mentioned means including a spring-urged striking shoe for clamping said warp yarns to the other of said loom beams, and means pivotally connecting said fastening means to said movable member.

10. A textile slasher beam-changer and winding mechanism for delivering a multiplicity of yieldable warp yarns to a plurality of loom beams each having an adhesive strip thereon comprising a base member, a rotatable frame mounted on said base member having a plurality of tail stocks on one end thereof and a plurality of complementary head stocks on the opposite end thereof, each complementary pair of head stocks and tail stocks being adapted to accommodate a replaceable loom beam, a plurality of clutch mechanisms, means for driving each of said head stocks through a separate clutch mechanism, means for revolving said frame to thereby change the relative positions of said loom beams, at least one of said loom beams being continuously rotated during said change of relative positions of said beams, a movable tension positioner and accumulator roll supported by the warp yarns and for continuously maintaining yarn tension during the uninterrupted delivery of warp yarns to said beam changer and winding mechanism, means for clamping said warp yarns at spaced portions thereof, and means for cutting said warp yarns between said clamped warp yarns, a movable member being provided with resilient means for yieldably supporting said cutting means; means for fastening said warp yarns to the other of said loom beams, said last-mentioned means including a spring-urged arcuate striking shoe for clamping said warp yarns to the adhesive strip on the other of said loom beams, and a pivoting lever connecting said fastening means to said movable member.

11. A textile slasher beam-changer and winding mechanism as set forth in claim 7 wherein said cutting means further includes an assembly for permitting the free fall of said cutting means in a downward direction but a multiplied movement of said cutting means in an upward direction.
